UNITED STATES PATENT OFFICE.

DANIEL A. WEDMORE, OF PHILADELPHIA, PENNSYLVANIA, ASSIGNOR TO PHILADELPHIA STEEL & WIRE CO., OF PHILADELPHIA, PENNSYLVANIA, A CORPORATION OF NEW JERSEY.

METALLIC REINFORCE FOR CONCRETE CONSTRUCTION.

972,961.

Specification of Letters Patent.

Patented Oct. 18, 1910.

Application filed July 9, 1907. Serial No. 382,826.

To all whom it may concern:

Be it known that I, DANIEL A. WEDMORE, a citizen of the United States, residing in Philadelphia, Pennsylvania, have invented 5 certain Improvements in Metallic Reinforces for Concrete Construction, of which the following is a specification.

My invention relates to the formation of composite concrete and metal structures of 10 various kinds, such as beams, floors, walls and other members of a similar nature; and the purpose of my invention is to provide an improved form of stirrup and spacing means for supporting the reinforcing bars for the 15 concrete in proper position with relation to each other, and to the form or mold in which the beam or other composite member is made. The purpose and use of metal reinforcements for concrete construction being well 20 known in the art, it is not thought necessary to describe the same herein.

My invention relates specifically to an improved form of stirrup and to spacing means combined with said stirrup, and is fully 25 shown in the accompanying drawings, in which:

Figure 1, is a sectional elevation of a mold or form, showing an improved form 30 of stirrup embodying my invention, and one form of spacer which I may use therewith; Fig. 2, is a similar view illustrating a slight modification of the spacer shown in Fig. 1; Fig. 3, is a perspective view of the spacer shown in Fig. 1; Fig. 4, is a view similar to 35 Fig. 1, showing a spacer for use therewith having side extensions; Fig. 5, is a perspective view of the spacer shown in Fig. 4, and Fig. 6, is a view illustrating a detail of my 40 invention. Fig. 6, is a perspective view of the stirrup or support shown in Fig. 1, showing a modified form of spacer employed therewith; Fig. 7, is a sectional elevation 45 of the structure shown in Fig. 6; Fig. 8, is a perspective view of spacing and supporting.

In Fig. 1, I have shown a stirrup comprising vertical members 1, connected at the bottom by a plain run 2, and having at the top inclined supporting arms 3, with offsets 4 at 50 the ends of said supporting arms in order to maintain such structure in a vertical position when placed in a mold or form without danger of tilting during the assembling

of the metallic reinforcing bars for the concrete. The offset portions may extend in 55 the same direction, or in opposite directions as indicated in the drawings.

The upper and lower reinforcing bars are indicated at 5 and 5^a respectively, and the lower series of bars 5^a are placed directly on 60 the lower runs 2 of the stirrups, and in the arrangement shown in Figs. 1 and 2, three bars are so placed.

The reinforcing bars are separated and the upper row 5 supported by spacers 6, in 65 the structures shown in Figs. 1, 2 and 4, and when the lower set of bars are in place, the spacers are disposed in proper engagement with the stirrup and dropped onto the lower set of bars 5^a, and then the upper 70 set of bars are placed on said spacer. The spacer 6 is clearly shown in Fig. 3, and consists of a flat piece of sheet metal of suitable thickness, having recesses 7 to receive the bars, and turned edges 8 or other means to 75 engage the vertical runs 1 of the stirrup. In this form of spacer as shown in Figs. 1 and 3, the notches or recesses 7 are offset with respect to each other, while in the form shown in Fig. 2, the notches or recesses are 80 directly above one another and the vertical width of the spacing member is proportionately greater.

In the structure shown in Fig. 4, I have 85 illustrated a modified form of spacer made of sheet metal and indicated at 6^a, which, in addition to having the notches 7 to accommodate the bars, has side projections 9 whereby the stirrup can be readily centered in the form or mold in which the reinforced 90 concrete structure is made.

In Fig. 6, I have shown a form of stirrup having coiled portions at the top of its vertical runs to support the outside bars of the upper set. These coils are indicated at 10 95 and the supporting arms 3 have the usual offset ends 4 to provide a suitable support and prevent tilting.

In Fig. 7, I have shown a sectional view 100 of another part of my improvements in which the upper run of bars is connected by a member 23 having a series of loops 24, one for each bar; the projecting ends of the latter for support upon the form having the inclined arms 3 and the horizontal portions 17 held in place by staples 18. When

2
in use, the member 23 will be mounted adjacent the stirrup having the looped portions 21, shown in Fig. 6.

If desired, the offset ends 4 of the supporting portions 3 of the stirrups may be secured by staples to the frame of the form or mold, although such securing is not essential.

I claim:

- 10 1. The combination, with a wire stirrup consisting of vertical runs and a cross member integral therewith, of a sheet metal supporting and spacing member constructed for engagement by reinforcing bars, said supporting and spacing member being vertically disposed and extending between the vertical runs of said stirrup and having its ends turned to form hooks for engagement with said vertical runs.
- 15 2. The combination with a stirrup comprising an integral U-shaped member, of a sheet metal supporting and spacing member carried by said stirrup and extending between the legs of the same, said spacing member being notched on its upper and lower edges for the reception of reinforcing bars.
- 20 3. The combination with a stirrup consisting of vertical runs and a cross member integral therewith, of a sheet metal supporting and spacing member for reinforcing bars having side clips in engagement with said stirrup and extending between the legs of the same, said spacing member being notched on its upper and lower edges for reinforcing bars.
- 25 4. The combination of a stirrup for reinforced concrete construction, and a sheet metal spacing and supporting member for reinforcing bars carried by said stirrup and extending between the legs of the same, said spacing member having side extensions forming positioning means.
- 30 5. The combination of a stirrup for sup-

porting reinforcing bars, and a sheet metal 45 spacing and supporting member for said bars carried by said stirrup, said spacing and supporting member having side extensions forming positioning means and hook portions to engage the legs of said stirrup. 50

6. The combination of a stirrup for supporting reinforcing bars, and a spacing and supporting member for said bars mounted for engagement with said stirrup, said spacing member having side extensions forming 55 positioning means and hook portions to engage the legs of said stirrup.

7. A combined support and spacer for use with reinforcing bars and supporting stirrups, said support and spacer being formed 60 of a single ply of sheet metal, having notches to accommodate said bars and integral hooks at its ends for engagement with the vertical runs of a stirrup.

8. A sheet metal support and spacer for 65 reinforcing bars having notches to accommodate said bars, side extensions serving as positioning means, and side clips for engagement with a stirrup.

9. A support and spacer for reinforcing 70 bars made of sheet metal and having notches in its upper and lower portions to accommodate said bars, and curved portions at its sides forming vertical clips for engagement with the stirrup. 75

10. A support and spacer for reinforcing bars having notches in its upper and lower portions to accommodate said bars, side extensions serving as positioning means, and side clips for engagement with a stirrup. 80

In testimony whereof, I have signed my name to this specification, in the presence of two subscribing witnesses.

DANIEL A. WEDMORE.
